ATTORNEY

UNITED STATES PATENT OFFICE.

WOLFGANG B. KLEMPERER, OF AKRON, OHIO, ASSIGNOR TO GOODYEAR-ZEPPELIN CORPORATION, OF AKRON, OHIO, A CORPORATION OF DELAWARE.

FLANGED FIN.

Application filed July 30, 1925. Serial No. 47,018.

My invention relates to airship construction and it has particular relation to the structure of horizontal and vertical fins adapted for use in connection with various types of rigid or non-rigid airships.

One object of my invention is to provide a novel type of airship fin which possesses relatively great efficiency as regards the ratio of weight to strength of the material of which the fins are formed.

Another object of my invention is to provide airship fins which are so reinforced that they are of relatively light weight and are so formed that they tend to aerodynamically enhance the stability of the airship upon which they are employed.

In the fabrication of structural elements for airships it is well known that one of the primary aims is to reduce, as much as possible, the weight of such elements and, at the same time, retain a maximum of strength. Airship fins of the type commonly known are constructed in substantially flat streamline formation and are positioned vertically or horizontally adjacent the tail of the airship.

According to the principles of my invention I have reinforced the fins by providing them with flanges or supplemental plane portions disposed at right angles to the main body portion thereof, thereby materially increasing the resistance offered to the bending load which is exerted on the edge of the fin by the air reaction when air currents strike obliquely against the fins. The flanges also serve as guiding walls to decrease the amount of air overflow escaping around the edges of the fins from the windward to the leeward side thereof. Thus the aerodynamical efficiency of the fin is increased and, accordingly, for the same degree of strength and stability, reduction in weight of the fin is secured. Furthermore, the flanges positioned vertically upon the top and keel fins assist the horizontal fins and those placed on the horizontal fins assist the vertical fins in performing their function. By applying reinforcing flanges to the fins, the distribution of air pressure thereover provides a relatively favorable and more uniform loading than occurs when conventional fins are employed.

For a better understanding of my invention, reference may now be had to the accom-

panying drawings forming a part of this specification, of which:

Fig. 1 is a fragmentary side-elevational view of an airship provided with fins embodying my invention;

Fig. 2 is a cross-sectional view of the structure illustrated in Fig. 1, the view being taken substantially along the line II—II of Fig. 1, and parts being omitted for the sake of clearness;

Fig. 3 is a fragmentary side-elevational view of an airship provided with fins embodying another form which my invention may assume;

Fig. 4 is a cross-sectional view taken substantially along the line IV—IV of Fig. 3; and

Fig. 5 is a diagrammatical view illustrating graphically the comparative distribution of forces as applied to fins constructed according to my invention and as applied to the conventional form of fins.

In practising my invention I have provided vertical fins 10 and horizontal fins 11 secured in a conventional manner to an envelope or hull 12. Each of the vertical fins is formed with a major vertically extending portion 13 and a supplemental portion 14, the latter consisting of flanges 15 extending along the outer edge of the fins at substantially right angles thereto. It will be observed that the fins as a whole are of T-shape in cross-section. At the rear end of the fins 10, the usual rudders 16 are provided. Each of the horizontal fins 11 is constructed to form a major substantially horizontally extending portion 16 and is provided with supplemental portion 17, consisting of vertically disposed flanges 18, similar to the vertical fins 10. Each fin 11 is provided with a conventional rudder 19. It will be observed that all of the major portions and the flanges are of streamline form.

Referring to the form of my invention illustrated in Figs. 3 and 4, vertical and horizontal fins 20 and 22, respectively, of streamline form, are secured to an envelope or hull 23 of an airship and are provided with flanges 24 and 25, respectively, positioned adjacent the edges of the fins and at right-angles thereto. In this form of my invention the major portions 26 and 27 of the fins 20 and 22, respectively, are substantially similar to portions 13 and 16, respec-

tively, shown in Figs. 1 and 2, but the flanges 24 and 25 in this instance are spaced from the outer edges of the fins so as to define a cruciform configuration in cross-section. 5 Rudders 28 and 29 are likewise secured to the fins 26 and 27, respectively.

The flanges 24 and 25 are preferably arranged substantially parallel to the natural airflow lines which occur at the zero angle 10 of air attack of the airship, i. e. when the airship proceeds on an even keel. However, it is to be understood that the airflow line direction at the location of these flanges may have a slight converging angle to the axis 15 of the airship. If for any reason the fin would have to be so designed that its outer edge could not follow the airflow line direction along a sufficient length thereof, the flange might depart from the edge at a certain 20 point and follow the airflow lines of no incidence along a sufficient length without however deviating too far from the edge contour of the fin, in order to retain a proper efficiency as a border overflow protection.

25 In order to more clearly explain the advantages of my invention over the plain form fin of conventional construction, reference may be had to Fig. 5. As illustrated in this figure by a curved graph 30, a fin 30 constructed without a flange, as indicated in dot and dash lines at 30°, is subjected to severe stresses at the edges thereof, as indicated by the peak of the load at 31. These stresses are caused by the strong eddy washing around the fin from the windward to the leeward side. On the other hand, the stresses upon a fin constructed with flanges, as indicated in dot and dash lines at 32°, are represented by a curved graph 32. The 35 highest point indicating the greatest load peak at 33, is materially lower than the point 31 representing the point of greatest stress in the non-flanged fin.

40 It will be noted that the flanges included in my invention are preferably applied to fixed fins, while the relatively movable parts of the airship, such as rudders and elevators, are of minor importance with respect to the edge stresses, as well as to the overflow protection. This is true because the area of the fixed fins is much greater than that of the movable surfaces and they have a minor aspect ratio. Even when the rudders are inclined, the greatest strain resulting 45 from air reaction occurs upon the fixed fins in front of the rudders.

From the foregoing description it will be apparent that I have provided a materially improved form of fin which is simple in construction and which performs the function of stabilizing the aircraft with relatively more efficiency than in any of the heretofore known structures.

60 Although I have illustrated but two preferred forms which my invention may assume and have described those forms in detail, it will be apparent to those skilled in the art that the invention is not so limited but that various minor modifications and changes may be made therein without departing from the spirit of my invention or from the scope of the appended claims.

70 What I claim is:

1. A stabilizing member for an elongate lighter-than-airship provided with an outer covering comprising a fin rigidly secured to the covering and disposed in a plane containing the axis of the airship, said fin being constructed with a flange adjacent one edge thereof and extending substantially parallel 75 to the axis of the airship.

2. A stabilizing apparatus for a lighter-than-airship provided with an outer covering comprising oppositely disposed substantially plane portions, each rigidly secured 80 to the covering and a plurality of plane portions disposed substantially at right angles to the first named plane portions.

3. In an airship having an elongate hull, a fin of substantially T-shape cross-section 85 rigidly secured adjacent one end thereof.

4. In an elongate aircraft, a fin rigidly secured thereto comprising a major plane portion and a minor integral portion, the combination of the portions defining a substantially T-shape in cross-section.

5. A stabilizing member for a lighter-than-airship provided with a hull comprising a plane portion rigidly secured to the hull and supplemental flanges following the 100 air flow lines of no incidence.

6. An aircraft fin formed with supplemental flanges slightly converging toward the stern of the aircraft.

7. A stabilizing member for a lighter-than-airship provided with a hull comprising a fin of substantially cruciform cross-section rigidly secured to the hull.

8. In witness whereof, I have hereunto signed my name.

WOLFGANG B. KLEMPERER.
